[57] CLAIM

The ornamental design for a sandal footbed, as shown and described.

DESCRIPTION

FIG. 1 is a top, front and right perspective view of a sandal having a sandal footbed visibly and ornamenteally exposed on the upper surface of the sandal sole and comprising my new design;

FIG. 2 is a top plan view of the sandal footbed;
FIG. 3 is a side elevational view of the sandal footbed;
FIG. 4 is a rear elevational view of the sandal footbed;
FIG. 5 is a front elevational view of the sandal footbed; and,
FIG. 6 is an enlarged view of a section of FIG. 5 indicated by the broken-line circle.

The broken line showing of the sandal in FIG. 1 is for illustrative purposes only, as the style of sandal per se forms no part of the claimed design.
